LADDER

William C. Kenyon, Pittsburgh, Pa.

Application August 19, 1933, Serial No. 685,869

3 Claims. (Cl. 304—4)

This invention relates to new and useful improvements in ladders, more particularly to collapsible standing ladders especially useful in preparing scaffolds for general uses such as 5 cleaning or painting buildings, and it is among the objects thereof to provide a combination standing and extension ladder which may be termed a jack ladder by virtue of the extension being adjustable vertically to any desired height.

10. A further object of the invention is the provision of a ladder which shall be adapted to the speedy construction of a scaffold without the use of nails, bolts or any other fastening means, and which shall be assembled as a unitary member to eliminate the handling of parts as is necessary in the making of scaffolds by the use of conventional supporting members.

Still a further object of the invention is the provision of a ladder which is self-supporting, 20 and which embodies an extensible member that is adapted to cooperate with movable elements fastened to the stationary parts whereby adjustments as to height and angular position may be speedily effected.

25. These and other objects of the invention will become more apparent from a consideration of the accompanying drawings constituting a part hereof in which like reference characters designate like parts and in which Figure 1 is a front elevational view of a scaffold constructed by the use of ladders embodying the principles of this invention; Figure 2 a side elevational view of one of the side elements of the standing ladder portion; Figure 3 a side elevational view of a 30 brace or support utilized in the construction of the scaffolds shown in Figure 1; Figure 4 a front elevational view of a different scaffold arrangement constructed of the ladder shown in Figure 1 and Figures 5 to 7 of the drawings; Figure 5 a side elevational view of the combined standing and extensible ladder; Figure 6 a similar view with special braces for supporting the scaffold planks; Figure 7 a view showing the extensible portion of the ladder partially retracted; 35

40. Figure 8 a view illustrating the extensible portion in collapsed position and showing in dotted lines the extension ladder as a leaning element; Figure 9 a front elevational view of a portion of the supporting ladder and the extension ladder; Figure 10 a top plan view of the structures shown in Figures 5 to 7 inclusive; Figure 11 a side elevational view of the ladders corresponding to the view of Figure 9; Figure 12 a top plan view of the hinge member; Figure 13 a front 45 elevational view of a portion of a center brace

or strut; Figure 14 a side elevational view of the part shown in Figure 13; Figure 15 a side elevation showing the ladders collapsed; and Figs. 16 and 17 side and end elevational views of an extension bracket.

With reference to the several figures of the drawings, the structure therein illustrated comprises a folding ladder and an extensible ladder, the folding ladder consisting of the uprights 1 and rungs 2 of gradually increasing length towards the bottom which is productive of a rather wide and substantial base when the ladders are spread. The two base ladders are hinged in the manner shown in Figure 11 of the drawings, the hinge consisting of brackets 3 which are integrally formed with plates 4 that overlap and are joined by a pivot pin 5, although other suitable hinge constructions may be employed. The pivot bolt 5 also pivotally holds a bracket 6 of a size to hold the extension ladder 7, this being illustrated in Figures 9 and 11 of the drawings. The members 6 are adapted to permit the extension ladder 7 to slide freely therein and at the same time they provide secure fastening means to firmly hold the extension ladder in its adjustable or extended positions.

The base ladders 1 and the extension ladder 7 are thus pivotally joined to permit folding or angular and vertical adjustment with the side ladders either spread as shown in Figures 1 to 8 of the drawings, or in the collapsed position as shown in Figure 15. The base ladders 1 are provided with through bolts 8 which extend through the side frames and are attached by means of screw nuts 9 co-acting with the threaded ends 10 of the bolt.

Cross-straps 11 are hinged at one end to the through bolt of one of the ladder frames and the straps are provided with a slotted end 11a as shown in Figure 11 which co-acts with the through bolt of the other ladder, the straps 11 carrying rods 12 and 12a as shown in Figure 10, these rods extending parallel with the through bolts 8 and transversely to the straps 11 to which they are attached.

The bar 12a is provided with fingers 13 which are secured to the bar at 14 to be movable with the bar which itself is mounted for angular movement in the cross-strap 11. The fingers 13 are designed to co-act with the rungs 7a of the extension ladder 7 to hold the ladder to any adjusted position as will be hereinafter explained. The fingers 13 are of sufficient weight to force the rod 12a to angular movement when they are moved by the rung of the ladder so

that the fingers will always drop on the rod 12 to act as a support for rungs 7a when the ladder is placed in any desired position.

In utilizing the jack ladder for constructing 5 a scaffold, as for example that of Figure 1 of the drawings, the extension ladders 7 are disposed in a horizontal position, and an upright 15 is disposed below the extended ends of the horizontal members, the uprights being provided 10 with a supporting bracket 16 as shown in Figure 13 of the drawings, which bracket is adapted to engage the rungs of the cooperating ladders to provide a substantial central support.

15 The ladder when set up in the manner shown in Figure 1 may be provided with a board of a width to fit between the side frames of the extension ladders, thereby completing the scaffold.

20 As shown in Figure 2, when the extension ladder 7 is in the horizontal position of Figure 1, there is a long step between the top rung 2 of the standing ladder and the horizontally disposed extension ladder, and for this reason brackets 17 are provided on each side of the standing ladder to permit stepping from the top rung onto the platform of the scaffold.

In Figure 4 of the drawings, the extension ladders 7 are disposed vertically to their uppermost extended position as shown in Figures 5 and 6 with the fingers 13 and fingers 10 supporting the lower rung of the extension ladder 7. The scaffold is constructed by extending a board 18 across the top rungs of the two extension ladders. If it is desired to change the height of the scaffold in the arrangement of Figure 4, either the board 18 is moved to lower rungs of the two ladders or else the ladders themselves are lowered by lifting fingers 13 which permit dropping them to any position desired when fingers 13 are again placed to engage the rung of the ladder to which position it has been moved.

If, in the construction of Figure 4, it is desired to provide a wide platform such as that shown in Figure 6, additional boards 19 may be supported on the stepladders by the use of clips or brackets 20 which are shown in detail in Figures 16 and 17 of the drawings. These clips 45 are so arranged that they engage the side of the ladder and interlock with the first and second rungs at the top whereby they are securely held and supported for the reception of the cross scaffold boards 19. The clips or brackets 20 are so constructed that they cannot be displaced without raising them clear of the rungs with which their depending portions 21 engage, and for this reason the scaffold is absolutely 50 safe as the weight on the boards will more firmly hold the clips in position.

In Figure 7 of the drawings, the extension ladder is shown extended about half way above the standing ladders, and in Figure 8 it is shown as a leaning ladder, the standing ladder 65 being spread as in the other views, but the extension ladder being exposed adjacent one of the side ladders, this being accomplished by lifting it entirely clear of the fingers 13 and dropping it to either side of the through bolts 8 as will 70 be apparent from Figure 10 of the drawings.

In Figure 15 the ladder is shown in its collapsed position to which position it is readily and conveniently changed by lifting the extension ladder clear of the fingers 13 and dropping it alongside of the through bolts in the

5 manner shown in Figure 8 so that when the extension ladder is entirely lowered the standing ladder may be collapsed by lifting the straps 11 clear of the through bolts which is permitted through the slotted connection 12, allowing it to drop which permits collapsing the standing ladder to the position shown in Figure 15.

Some of the convenient and accessible features of the jack ladder construction hereinbefore described are the quick adjustments made 10 possible by the use of the fingers 13 and the general arrangement and construction of the ladder, particularly the sliding connection of the extension ladder through the hinge bracket 6 which permits sliding of the extension ladder 15 and pivotal movement as well so that it may be disposed either between the cross bars or rods 12 as shown in Figure 10 where it will engage the fingers 13 or else it may be readily disposed between the bars 12 and the through 20 bolts 8 without resting on the fingers 13.

When the extension ladder is in its lowermost position, and disposed between the rods 12, it can be speedily adjusted to any height by simply pulling it vertically upward until the particular rung which passes the fingers 13 gives the desired height when it is lowered to rest upon the fingers 13, and in this position, it is securely held by the slide brackets 6 and the fingers 13.

30 By means of the construction of the jack ladder hereinbefore described, many different arrangements of scaffolds can be provided without the use of fastening screws or bolts or without requiring any nailing of cross boards or other 35 structural elements.

It is evident that various modifications of the detailed construction herein disclosed may be made without departing from the principles 40 herein set forth.

I claim:

1. A scaffold comprising a plurality of ladders comprising each a pair of base ladders adapted to be spread, having an extension ladder extending centrally thereof and adjustable to various 45 heights, means for mounting said extension ladders on hinged brackets adapting them to pivotal movement relative to the base ladder whereby the extension ladders may be disposed horizontally relative to the feet of the base ladders 50 and a strut adapted to cooperatively engage the extended ends of the extension ladders whereby to form a horizontal scaffold.

2. The combination with a plurality of base ladders of extensible members pivotally mounted 55 at the top of said base ladders, locking means for securing said base ladders in their spread position, hinge brackets pivoted at the hinged portion of said ladders, said bracket having guide ways for gripping the sides of the extension 60 ladders, which guide ways are of a size to provide a substantial area of contact with said extension ladders and adapted to hold them in adjusted angular positions, through bolts extending from the rungs of the base ladders and having cross straps thereacross, bars in parallel 65 relation secured to said cross bars having hinged members pivotally connected to one bar and adapted to be supported on the other bar, said hinge members lying in the path of movement of said extension ladder whereby they are adapted to form supporting abutments for the rungs of said extension ladder, when it is adjusted to vertical position, and scaffold boards 70 mounted on the rungs of said extension ladders. 75

3. A scaffold comprising a plurality of ladders comprising each a pair of base ladders adapted to be spread, having an extension ladder extending centrally thereof and adjustable to various heights, means for mounting said extension ladders on hinged brackets adapting them to pivotal movement relative to the base ladder,

shelf brackets mounted on said extension ladder having rung engaging portions for interlocking engagement with the sides and rungs of said extension ladder, and scaffold boards supported by said brackets.
